UNITED STATES PATENT OFFICE.

EDWARD S. STIMPSON, OF HOPEDALE, MASSACHUSETTS, ASSIGNOR TO DRAPER COMPANY, OF HOPEDALE, MASSACHUSETTS, A CORPORATION OF MAINE.

SELF-THREADING LOOM-SHUTTLE.

SPECIFICATION forming part of Letters Patent No. 692,801, dated February 4, 1902.

Application filed October 7, 1901. Serial No. 77,852. (No model.)

To all whom it may concern:

Be it known that I, EDWARD S. STIMPSON, a citizen of the United States, and a resident of Hopedale, county of Worcester, State of Massachusetts, have invented an Improvement in 5 Self-Threading Loom-Shuttles, of which the following description, in connection with the accompanying drawings, is a specification, like characters on the drawings representing 10 like parts.

This invention relates to loom-shuttles provided with means whereby the filling-thread is automatically directed to a delivery-eye after a fresh filling-carrier has been inserted automatically in the shuttle to take the place of the filling-carrier previously held therein.

Various automatically self-threading shuttles have been devised which are successful in practice in so far as the threading operation is concerned; but considerable trouble has been experienced by a bight or loop of the thread formed between the filling-carrier and the inner end of the threading device throwing and catching upon either the point or 20 beak of the head overhanging the horn or some other part of the threading device. This looping of the thread is caused by the sudden stoppage of the shuttle in the shuttle-box and too rapid delivery of the thread from the 25 filling-carrier, the slack forming a loop, which is thrown out toward the point of the shuttle. Sometimes the shuttle will for this reason be unthreaded; but more often the loop catches and the thread will be broken just 30 as soon as the flight of the shuttle exerts sufficient tension on the thread to draw the loop taut around the obstruction.

My present invention has for its object the production of a shuttle of the type referred 40 to provided with means for preventing the loop of thread, if formed, from catching and causing breakage of filling, the novel threading device forming the subject-matter of this invention facilitating the automatic self-threading of the shuttle and being very simple in construction and effective in operation.

Figure 1 is a top or plan view of a loom-shuttle embodying one form of my invention, a filling-carrier being shown in place and the

shuttle threaded. Fig. 2 is an enlarged transverse section on the line 2-2, Fig. 1, looking toward the right; and Fig. 3 is an enlarged perspective view of the threading device or block.

The shuttle-body A, open at top and bottom, is provided with suitable jaws A' to receive and grasp the head of a filling-carrier B, Fig. 1, the shuttle-body having a side delivery-eye a^x and being cut out longitudinally beyond the tip of the filling-carrier to receive 60 the threading device.

The threading-block (shown separately in Fig. 3) comprises two parallel longitudinal side walls d' d', connected at their bases at d^x and having at their inner ends a transverse 65 connecting-wall d², extended laterally to form upright ears d³, which fit into pockets 2 in the shuttle-body, Fig. 1, to assist in positioning the block. The greater portion of the wall d is reduced in height, as at d⁴, and a trough or 70 open longitudinal passage d⁵ is formed between the walls at their base, said passage forming a forward continuation of a tubular opening or inlet d⁶ in the wall d², the part d⁷ and said inlet constituting the thread-passage 75 in which the thread travels from the filling-carrier to the delivery-eye. Above the inlet the wall d² is recessed from its top downward in continuation of the inner faces of the walls d' d' to form a wide thread-entrance d⁸, 80 which communicates at its bottom with the inlet by a narrow longitudinal slot d⁹, and a downturned curved guard g is extended from at or near the top of said entrance overhanging the slot d⁹. The guard projects from the side 85 wall d', and its lower edge approaches closely the opposite face of the thread-entrance, said face being preferably beveled or convexed at its top, as clearly shown at 30 in Figs. 2 and 3, and the narrow slot d⁹ is inclined toward the 90 wall d' for a purpose to be described. The front edge of the wall d' is upwardly and forwardly inclined to constitute a horn d¹⁰, and a flat substantially triangular head d¹¹ is formed on said wall above the horn, the tip 95 or point of the head being downturned to constitute a prong or spur d¹². This head extends above and across the open portion of

- the thread-passage, the shuttle-body being recessed beneath the head, as at 5, Fig. 1, the inner edge d^{13} of the head extending diagonally from the tip rearwardly to the back of the head, which presents a transverse shoulder d^{14} in front of but separated from the thread-entrance d^7 by a considerable distance, leaving an unobstructed open space therebetween.
- 10 The threading-block is secured in the shuttle-body in any suitable manner, as by a screw 15, (see dotted lines, Fig. 2,) extended through a transverse hole 8 in the block below the thread-passage.
- 15 When the filling-carrier is inserted in the shuttle, the free end of the thread t is held fast, and when the shuttle is thrown to the left, viewing Fig. 1, the thread draws off over the tip of the filling-carrier and is drawn down across the edge d^{13} of the head and enters the thread-entrance d^7 , passing down between the convex face of the guard g and the opposite face of the said entrance and underneath the lower edge of the guard. At about this time the thread will have also been shed from the head, the edge d^{13} being preferably beveled at d^{15} , adjacent the shoulder d^{14} , to facilitate the shedding of the thread over said edge, and the thread passes under the head and between the spur d^{12} and the recessed portion 5 of the shuttle-body ready to completely enter the thread-passage. After the thread passes under the guard g it is drawn down by its tension through the slot d^8 into the tubular inlet d^6 and then is well in its proper position in the open and tubular parts of said thread-passage. On the next throw of the shuttle to the right the thread is guided by the horn d^9 to the delivery-eye a^x , and the shuttle is thus threaded, the thread being delivered thereafter from the delivery-eye.
- The rotative movement of the thread as it is drawn from the filling-carrier is from right to left, viewing Fig. 2, so that the opposite 45 inclination of the slot d^8 tends to prevent the thread from flying up or slipping out from the inlet d^6 through said slot; but if it should pass therethrough the inclination of the slot directs it into the pocket formed by the guard 50 g , and the concave face thereof immediately directs the thread back through the slot into the thread-passage.
- Should a loop of thread be thrown out and forward, it will fall over the guard g and thence into the long open space between the thread-entrance and the head and will be drawn into said entrance as soon as tightened by the flight of the shuttle without being caught and broken.
- 60 The point of the head is so far removed from the rear end of the threading device that it is a practical impossibility for a loop of thread to catch on the point.
- By cutting away and reducing the height 65 of the wall d , as described, the space forward of the thread-entrance and above the open

part d^5 of the thread-passage is made larger and readier of access by a thread-loop, the diagonal edge d^{13} of the head also assisting to direct a loop into such space.

I prefer to make a slight concavity 40 in the rear edge of the guard g , near the top thereof, to direct a loop of thread over toward the wall d when thrown out, so that the guard will stop further forward movement thereof, said 70 concavity also acting to temporarily hold the thread during the threading operation until the shuttle is thrown well out of the shuttle-box, so that the thread will not have a tendency to enter the thread-entrance too soon to 80 clear the picker.

In practice the threading device operates accurately and surely, positively prevents breakage of the thread due to looping and catching, as there is nothing for the loop to 85 catch upon, and unthreading is most effectively obviated, while the general shape of the block reduces very materially the necessary cutting away of the shuttle-body to receive it.

Having fully described my invention, what 90 I claim as new, and desire to secure by Letters Patent, is—

1. In an automatically self-threading shuttle, a block having in its base a longitudinal thread-passage having a short tubular portion 95 at its rear end, a thread-entrance above said portion and communicating therewith by an inclined, narrow slot, a downturned guard in the entrance overhanging the slot, the inclination of the latter being toward the pocket 100 formed by the guard, and a horn the head of which extends over the front end of the thread-passage, the back of the head being at a distance from the thread-entrance and leaving an open space between them. 105

2. In an automatically self-threading shuttle, a block having in its base a longitudinal thread-passage having a short tubular portion at its rear end, a thread-entrance above said portion and communicating therewith by a 110 narrow slot, a downturned guard in the entrance overhanging the slot, and a horn the head of which extends over the front, open portion of the thread-passage, the back of the head constituting a shoulder extended 115 laterally in front of and at a distance from the guard.

3. In an automatically self-threading shuttle, a block having longitudinal parallel side walls one of which is higher than the other 120 and having its front end inclined to constitute a horn, an overhanging head on said wall above the horn, a transverse connecting-wall at the rear end of said side walls and having a tubular longitudinal opening therein constituting the inlet end of the thread-passage, a thread-entrance in said transverse wall above and communicating at its bottom with the tubular opening by a narrow slot, and a 125 downturned guard in said entrance, mounted 130 on the high side wall and overhanging the slot, the front end of the thread-passage lead-

ing from the tubular opening and extending between the side walls at the lower portion thereof to the horn.

4. In an automatically self-threading shuttle, a long, longitudinal thread-passage open for the greater part of its length and having a tubular inlet at its inner end, a wide thread-entrance above said tubular inlet and communicating therewith by a narrow slot, a guard in said entrance overhanging the slot, and a horn having its head overhanging the front open end of the thread-passage and leaving an unobstructed opening between the back of the head and the thread-entrance.
- 15 5. In an automatically self-threading shuttle, a long, longitudinal thread-passage open for the greater part of its length and having a tubular inlet at its inner end, a wide thread-entrance above said tubular inlet and communicating therewith by a narrow slot, a guard in said entrance overhanging the slot, and a horn having its head overhanging the front open end of the thread-passage, the inner edge of the head being diagonally extended across the said passage and leaving an unobstructed opening between the thread-entrance and the point of the head.
- 25 6. In an automatically self-threading shuttle, a long, longitudinal thread-passage open for the greater part of its length and having

a tubular inlet at its inner end, a wide thread-entrance above said tubular inlet and communicating therewith by a narrow slot, a guard in said entrance overhanging the slot, and a horn having its head overhanging the front open end of the thread-passage, the back of the head presenting a transverse shoulder in front of the thread-entrance and separated therefrom by an unobstructed opening.

- 35 7. In an automatically self-threading shuttle, a long, longitudinal thread-passage open for the greater part of its length and having a tubular inlet at its inner end, a wide thread-entrance above said tubular inlet and communicating therewith by a narrow slot, a guard in said entrance overhanging the slot, and a horn having its head overhanging the front open end of the thread-passage, the inner edge of the head being extended rearward from its tip diagonally to the transverse back 45 of the head and beveled adjacent the back, to shed the thread from the top of the head.

In testimony whereof I have signed my name to this specification in the presence of two subscribing witnesses.

EDWARD S. STIMPSON.
